MAILBOX

Clark F. Swanson, Cologne, Minn.

Application March 27, 1946, Serial No. 657,382

5 Claims. (Cl. 232—25)

1

This invention relates to improvements in mail boxes for rural delivery mail routes.

The primary object of the invention is to provide a mail box of this character large enough in size to accommodate parcel post packages, as was once the requirement by the postal department and is now desired by the carrier, but having a novel door arrangement overcoming the most undesirable feature of previous boxes. As will be understood, a mail box if large enough to receive parcel post packages will have a front end of considerable height, and heretofore it has been the practice to hinge this large end at its bottom to operate as the door for access to the interior of the box. This is in accordance with the usual construction of rural mail boxes, but in the case of these large boxes the door, when opened, projects so far forward from the box that the mail carrier cannot reach over the door to the interior of the box from his car window. In accordance with this object of my invention I provide a small door at the lower front and center of the box which may be readily opened to place letters or small packages in the box, or remove outgoing mail therefrom, and then form the remainder of the front end of the box in two horizontally swingable doors or sections which may be opened to place larger parcels in the box, and by thus breaking up the front of the box into several separately hinged doors all may be opened without projecting further from the box than does the small door of the size heretofore employed in smaller boxes.

Another object of my invention is to improve the letter support for outgoing mail and the flag arrangement for indicating to the carrier that such outgoing mail is in the box.

Still another object is to provide an improved mounting and supporting structure for rural mail boxes, overcoming many objectionable features of previous supports.

These and other more detailed and specific objects will be disclosed in the course of the following specification, reference being had to the accompanying drawings, in which—

Fig. 1 is a frontal elevation of my improved mail box, closed.

Fig. 2 is a plan view of the front end of the box, showing it opened.

Fig. 3 is an enlarged fragmentary detail sectional view along the line 3—3 in Fig. 1.

Fig. 4 is a side elevation of the box and its supporting structure, with a part of the box broken away to show interior construction.

2

Fig. 5 is a view similar to Fig. 3 but showing the box opened.

Fig. 6 is an enlarged fragmentary sectional view along the line 6—6 in Fig. 3.

Referring to the drawing now more particularly and by reference characters, I show therein a mail box having the usual shape and comprising a rectangular bottom 10 corrugated lengthwise as shown, sides 11 and 12 connected by an arched top 13, a closed rear end 14 and an open front end 15. Framing details of the box, being unimportant to my invention, will not be described except that it will be noted that a cross member in the form of an angle iron 16 extends crosswise beneath the front end of the bottom 10. The open forward end of the box is normally closed by a centrally located primary door 17 and two similar side or auxiliary doors 18 and 19 and to afford an idea as to the size of the box the door 17 is substantially the shape and size of the front end of the rural mail boxes of the small sizes used so commonly heretofore. Thus it will be evident that my box is of such size that large parcels may be readily accommodated therein.

The center door 17 is shaped to correspond with the arched top of the box itself and is much narrower and shorter than the open end of the box. The side doors 18 and 19 are accordingly complementarily shaped to close the balance of the opening about the sides and top of door 17, being thus notched at lower center portions 20 and meeting, when closed, along an upright center line 21 upward from the center door. Actually the margins of the door 17 will overlap the contiguous margins of the doors 18—19 so that the front of the box will be weather-tight when the doors are closed.

The lower edge of door 17 is hinged to the box by hinges 22 fastened to the door and to the cross member 16 by rivets, or any other suitable fastening means, and the door may thus swing forward and downward as it is opened in the usual fashion. This opening movement is limited, to stop the door when fully opened in a substantially horizontal position (Fig. 5) by a strap 23 secured vertically to the center of the door and depending in the form of an upwardly and rearwardly turned stop finger 24 behind the cross member 16. As clearly shown the finger 24 will contact this cross member when the door is opened, preventing further downward movement of the door. The opposite upper end of the strap 23 is formed into a finger hook 25 as a convenience in pulling the door open.

In addition to its function as a stop, the finger

24 also cooperates with the downwardly turned looped center 26 of a torsional coil spring 27 the ends of which are secured at 28 to the cross member 16. When the door is closed the finger 24 engages the bottom of the loop 26 of the spring (Fig. 3) and the spring tension serves to hold the door in such position. As the door is pulled downward, however, the finger passes upwardly and forwardly through the loop (Fig. 5) of the spring relieving the door of the spring tension somewhat so that the door will remain opened until slightly lifted whereupon the spring will reassert itself to snap the door shut.

The doors 18 and 19 are hinged at their outer vertical edges, at 29 and 30 respectively, to the forward edges of the box sides 11 and 12 to swing in horizontal planes. A spring latch 31 is secured at 32 to the top center of the box and depends over the adjacent upper and inner corners of the doors 18 and 19 to normally hold them closed but by springing the latch upwardly it will clear the doors so that they may be opened.

It will now be apparent that the center door 17 alone may be opened when letters or small packages are to be placed in or removed from the box, but that when a larger opening is needed to clear large parcels, such as egg cases, packages and the like, the doors 18 and 19 may be also opened to expose the entire front of the box. However, as seen in Fig. 2, there at no time is formed any forward projection greater than that of the small center door 17, so that the mail carrier will have no difficulty in reaching into the box from his car window. Obviously this would not be the case were only a single door used since, when opened, it would project so far forward that the carrier could not approach the box close enough to reach into it. Little effort or time is required to open and close the three doors and certainly not enough to counteract the convenience with which access is had to the box with my invention.

I also provide a novel carrier or clip for outgoing letters and a cooperating signal flag arrangement which will now be described. Adjustably secured by rivets or similar fasteners 33 to the inside of the door 17, near its bottom, is one end of a slightly bowed spring 34 and secured at 35 to opposite sides of this fastened end of the spring 34 are the ends of a looped wire clip 36 having torsion coils 37. The sides of the looped clip 36 clear spring 34 and the bight 38, where it crosses the spring, is bent angularly inward so that it will not bear on the spring. Affixed to or extended from the free end of the spring 34 is a hook 39 which turns outwardly and plays in a slot 40 in the door and terminates in a downwardly turned end 41. A signal flag 42 in the form of a rectangular piece of metal, painted red in accordance with usual practice, is attached to one end of a wire stem 43 which has a pintle portion 44 turned horizontally and freely pivoted in a hinge 45 affixed at the center forward and lower portion of the door. From this pintle portion 44 there depends an actuator finger 46 turned rearwardly and upwardly beneath the cross member 16 alongside the aforesaid stop finger 24.

The flag 42 pivots upon the stem 43, being formed with punched out hinge ears 47 for this purpose and there are located off center in the flag so that it will tend by gravity to pivot upon the stem to the position of Fig. 3 whereat it will be stopped by an angularly turned end 48 on the stem as will be evident. The flag is further so

located that normally the hook end 41 will engage its upper edge (Fig. 1) and hold it flat against the door 17 in inoperative position.

In operation, then, an outgoing letter A may be placed in the box by slipping it between the spring 34 and clip loop 36 as shown in Figs. 3 and 5 where it will be held by the spring tension of these parts. Also the letter tends to flatten the bowed spring 34, by the pressure against the letter of the clip 36, and as a result the spring 34 is in effect elongated and the hook end 41 is moved clear of the flag 42 as seen in Fig. 5. The door 17 is, of course, opened to the position shown in Fig. 5 when the letter is put in place and when the door is then closed the off center weight of the flag will cause it to fall forward and project from the front of the box at right angles to the road so that it will be readily seen by the approaching mail-carrier. When the carrier then opens the door 17 to remove the letter A, the finger 46 strikes the cross member 16 as shown in Fig. 5 folding the flap back flat against the door and when the letter is withdrawn the spring 34 will return to its bowed shape reengaging the hook end 41 with the flag. As the door is then closed again the flag will be held in its normal position. Thus the setting of the flag is entirely automatic and requires no attention at all upon the part of the farmer or carrier.

For supporting my mail box I also provide a novel supporting assembly shown in Fig. 4 comprising a pipe 49 secured horizontally at its front and back in the top of the box. The forward end of this pipe is secured by a bracket 50 to the upper center and forward edge of the box while the rear end extends loosely through a clip 51 depending at the rear top of the box, so that another pipe 52 may be forwardly telescoped over pipe 49 thus forming a boom of adjustable length. The pipe 52 is provided with a set screw 53 and at its rear end is secured by an elbow 54 to an upright pipe 55 which in turn depends telescopically into the open upper end of a pipe 56 secured in an upright position in the ground, preferably in a concrete footing 57. The pipes 49 and 52 may obviously be relatively adjusted and locked by the set screw 53 to support the mail box at any desired distance toward the road from the point at which the main support pipe 56 is anchored, thus making it possible to place pipe 56 well back from the road where it will be clear of and safe from road graders and other maintenance equipment.

The height at which the box is supported is also adjustable by the telescopic relation of the pipes 55 and 56 and may be locked at any such adjustment by a collar 58 secured to the pipe 55 by a set screw 59. The lower end 60 of the collar 58 is cut off at an angle downwardly toward the road and the upper end of the pipe 56 is oppositely angled as designated at 61. Thus the pipe 55 may rotate within the rigid pipe 56 and the box may swing with the boom to either side to clear a road grader, or to prevent damage by snow thrown aside by a snow plow, but when released the weight of the box, and angle of the meeting surfaces 60 and 61 will return the box to its normal position.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A door structure for a rural mail box having an open front end, comprising a center door hinged to swing forward and downward and adapted to close only a lower center part of said open end, and side doors hinged to swing outwardly and forwardly and adapted to cooperate to close the remaining side and upper portions of said open end.

2. A door structure for a rural mail box having an open front end, comprising a center door hinged to swing forward and downward and adapted to close only a lower center part of said open end, side doors hinged to swing outwardly and forwardly and when closed meeting along a vertical line extending upwardly at the center 15 of said open end.

3. A door structure for a rural mail box having an open front end, comprising a center door hinged to swing forward and downward about a horizontal hinge axis, and side doors hinged to swing outwardly and forwardly about upright hinge axes, all of said doors cooperating when closed to entirely close the said open end of the box.

4. A door structure for a rural mail box having an open front end, comprising a center door hinged to swing forward and downward and adapted to close only a lower center part of said open end, and side doors hinged to swing outwardly and forwardly and adapted to cooperate 25 to close the remaining side and upper portions of

said open end, the said center door overlapping the contiguous margins of said side doors whereby the center door must be opened in order to open said side doors.

5. A door structure for a rural mail box having an open front end, comprising a center door hinged to swing forward and downward and adapted to close only a lower center part of said open end, side doors hinged to swing outwardly and forwardly and adapted to cooperate to close the remaining side and upper portions of said open end, and separate means for normally releasably holding the center and side doors in closed positions.
